UNITED STATES PATENT OFFICE.

JOHN DORN, OF CHICAGO, ILLINOIS.

CURTAIN-FIXTURE.

SPECIFICATION forming part of Letters Patent No. 443,188, dated December 23, 1890.

Application filed March 10, 1890. Serial No. 343,278. (No model.)

To all whom it may concern:

Be it known that I, JOHN DORN, a citizen of the United States, residing at Chicago, in the county of Cook and State of Illinois, have 5 invented a new and useful Improvement in Curtain-Fixtures, of which the following is a specification.

My invention relates to an improvement in curtain-fixtures of the kind which serve to 10 support the curtains and enable them to be opened and closed by movement back and forth upon the support.

My object is to provide an improved curtain-fixture of the above class affording 15 means for readily hanging or removing the curtain of a particularly effective construction and manner of operation and capable of application in a manner to prevent its detracting from the ordinary ornamental quality of 20 such devices.

In the drawings, Figure 1 is a view in elevation of my improved mechanism supported upon the rear side of a cornice and showing the spring in its expanded condition to produce 25 closing of the curtain, of which only the upper portion is represented; Fig. 2, a similar view of the same, showing the spring compressed to produce opening of the curtain; and Fig. 3 is a front view, and Fig. 4 a side 30 elevation, of a preferred form of sheave and pawl for holding the cord.

A is a support, which may be in the form of a cornice, as shown, to extend across the top of a window or door, and which may, furthermore, be rendered as attractive in appearance as desired.

B is a rod secured at opposite ends upon the rear side of the support to extend lengthwise thereof, being out of contact with the 40 support between its ends.

The spring C is preferably of the automatically-expansible order and is of the zigzag form shown, coiled at the angles to increase its resistance and produce the eyes t on the 45 one side and eyes t' on the other, and it should be bent or coiled at the center of each section between the angles to form eyes s, located in direct line with each other to enable the rod B, thus forming a guide, to be passed through 50 them, as shown. The spring is compressed somewhat between the ends of the rod B, so that its resilient tendency causes it normally

to press with desired force against the end portions of the rod.

D is a cord or other flexible medium secured 55 at one end to an end of the spring and extending along the latter over a suitable sheave E or the like to hang down from one side of the device within easy reach of an operator. The sheave I prefer to employ is provided 6c around its periphery with notches r of the depth approximately of the groove of the sheave, and a pivotal dog q is supported adjacent to the sheave to enter the notches r.

When the curtain is drawn by means of 65 the cord D against the resistance of the spring, and it is desired to secure it in any adjusted position against the resilient action of the spring, the dog q is permitted to enter one of the notches r, which prevents return 70 rotation of the sheave, and to engage and bind the cord against the grooved surface of the sheave, which prevents the cord from being drawn across the sheave in the direction of the spring's resilience.

The curtain may be secured by means of 75 ordinary hooks x to the eyes t, and thus be suspended from the spring. When it is desired to open the curtain, the cord D is pulled to contract the spring, which as it slides along 80 the rod B draws the farther end and intervening width of the curtain in equal folds toward the sheave. By slowly relaxing the cord D the engaging end of the dog may be made to enter one of the notches r and bind the cord 85 to hold the spring in any desired compressed condition. To close the curtain the cord is pulled sufficiently to release the engagement of the dog therewith, when by letting go the cord or relaxing it quickly the spring will expand by its resilience along the rod and close 90 the curtain, while the consequent quick rotation of the sheave will prevent the dog from exerting its engaging effect.

If desired, the spring C may be one automatically compressible instead of expansible in its nature, which would be the character of the spring shown, for instance, if the eyes t t' were produced by coiling the wire in the contrary direction. When the spring is of 95 the compressible construction, it should be firmly secured at one end to the end of the rod B opposite the sheave, and the cord secured to the spring at the end of the latter 100

nearest the sheave, whereby the spring will operate normally to maintain the curtain opened, and pulling the cord will produce closing of the curtain against the resilient force of the springs.

Obviously, for two curtains the mechanism described may be duplicated.

The cornice A affords a support which operates to conceal the mechanism and is desirable on that account; but it is not indispensable, as the rod B and other mechanism may be secured directly upon the window or door casing and concealed behind or within a shield of any desired character, or it may be left exposed.

What I claim as new, and desire to secure by Letters Patent, is—

1. In a curtain-fixture, the combination of a guide-rod, a spring of zigzag form extensible and compressible along the rod and affording means for the attachment at intervals of a curtain and provided with eyes *s* to engage and slide upon the rod, and a cord or the like secured to one end of the spring and affording means for operating it to open and close the curtain, substantially as described.

2. In a curtain-fixture, the combination of a guide-rod, an automatically-expansible

spring of zigzag form extensible and compressible along the rod and provided with eyes *t* at which to attach the curtain and with eyes *s* to engage and slide upon the guide-rod, and a cord or the like secured to one end of the spring and affording means for operating it to open and close the curtain, substantially as described.

3. In a curtain-fixture, the combination of a guide-rod, an automatically-expansible spring of zigzag form extensible and compressible along the rod and provided with eyes *t* at which to attach the curtain and with eyes *s* to engage and slide upon the rod, a sheave or the like mounted at one end of the guide-rod, a cord or the like secured to the spring at the end thereof opposite the sheave and extending around the latter to afford means for operating the spring to open and close the curtain, and automatic gripping means, as the dog *q*, for engaging the cord and holding it against the resilient force of the spring, substantially as and for the purpose set forth.

JOHN DORN.
